Design No. 453
J. H. Sailor, Designer to Mr. Harrison on Chase
Design for a Doorway or Screen
Patented 27. April 1832

Des. 453

Samuel H. Sailor of Philadelphia, Pa.

Assignor to

North. Garrison & Chase of Philadelphia, Pa.

Letters Patent No 453. Dated April 27th 1852.

The schedule referred to in these Letters Patent and making part of the same

To all whom it may concern:

Be it known that I, Samuel H. Sailor, of the City and County of Philadelphia and State of Pennsylvania, have invented or produced a new and original design for a cooking stove; and I do hereby declare that the following is a full and exact description of the same, reference being had to the accompanying drawings, making part of this specification, in which

Fig. 1. is a side elevation of said cooking stove, and Fig. 2. an end elevation of the same. Like letters refer to like parts in both figures.

d & f. are square raised panels on two of the doors of the stove; and e; i; i; oblong raised panels on the other doors; each panel being bordered with a series of mouldings a. In the center of each panel is a small plane surface m, a little raised above the panel, square in the square panel, and rhombic in the oblong panels; and arranged diagonally on them. On each quarter of each central figure is a small low pyramid, whose base corresponds in shape with that of the figure, leaving a small space between one another, and on the edges of the figures, on which they stand. Around the above described central figures of each panel is a series of raised, angular, converging rays n, of circular form on the square panels, and elliptical on the oblong panels. Along each diagonal of the panels are several conical rods l, in relief, pointing and extending into the central figures and dividing the series of rays; the one directly on the diagonal being longest and largest, each hair next in order from the central one being gradually shorter and smaller. The panel h. is destitute of the series of rays, and has its conical rods arranged lengthwise of the oblong panel. The ornament at c. in Fig. 1. is similar to that on the panel h. The legs g; g; g; are adorned with

curved modifications of the converging conical rods in relief.

What I claim as my invention and desire to secure by Letters Patent, is the design and configuration of the conical rods *l*, series of converging angular rays *n*, central figure *m*, & leg *g*, as herein described, forming an ornamental design for a cooking stove.
